**COMPOSITE FISH LURE, CAN OPENER
AND BOTTLE OPENER**

Lloyd L. Pfahler, Columbus, Ohio

Application February 8, 1957, Serial No. 44,803

Term of patent 14 years

(Cl. D31—4)

Fig. 1.

Fig. 2.

Fig. 3.

Figure 1 is a side elevational view of a composite fish lure, can opener and bottle opener, showing my new design;

Figure 2 is a top plan view thereof; and

Figure 3 is a bottom plan view of Figure 1.

I claim:

The ornamental design for a composite fish lure, can opener and bottle opener, as shown.
